CARL D. BROWN, OF HOPEDALE, MASSACHUSETTS, ASSIGNOR TO DRAPER CORPORATION, OF HOPEDALE, MASSACHUSETTS, A CORPORATION OF MAINE.

WARP STOP MECHANISM FOR LOOMS.

Application filed August 2, 1924. Serial No. 729,770.

To all whom it may concern:

Be it known that I, CARL D. BROWN, a citizen of the United States, and a resident of Hopedale, in the county of Worcester and State of Massachusetts, have invented an Improvement in Warp Stop Mechanisms for Looms, of which the following description, in connection with the accompanying drawings, is a specification, like characters on the drawings representing like parts.

This invention relates to warp stop mechanisms for stopping the loom when a warp thread breaks or becomes too slack for weaving purposes.

As now ordinarily constructed, mechanical warp stop mechanisms comprise a series of drop wires and a detector which is given a detecting movement and is arrested in this movement when a drop wire fails to be supported by a warp thread. The strain placed upon the unsupported drop wire in arresting movement of the detector frequently causes injury to the drop wire through the actuating strain, because the drop wires themselves are usually made of light material and are consequently easily injured. In this ordinary type of warp stop mechanism, also, the drop wire guide for guiding the drop wires in their movements frequently becomes bent due to the strain placed upon the drop wire guide when the loom is to be stopped.

In the ordinary warp stop mechanisms now in use lint frequently accumulates on the drop wire guide and on the detector, with the result that impaired action of the parts frequently ensues.

Still another factor in the use of a warp stop mechanism as now ordinarily constructed is that the warp beam must be set back in order to have the proper stretch from the stop motion to the back harness.

The present invention seeks to overcome the difficulties and objections heretofore encountered in warp stop mechanisms, and an important feature of the present invention consists in means actuated by a drop wire when it fails to be supported by a warp thread during weaving for the actuation of a lock which operates to lock the detector to a fixed part of the loom, thereby relieving the stopping strain heretofore usually transmitted directly to the drop wire itself.

Another important feature of the invention consists in a drop wire engaging member of the detector, sufficiently yieldable to prevent injury to the drop wire, and yet sufficiently stable to effect operation of the lock by the drop wire; and a still further important feature of the invention consists in a drop wire guide which will flex or yield under the disturbing influence of a drop wire when it is in stopping position, and will resume its straight or unbent condition when the strain is removed.

In accordance with the present invention, the wire engaging member of the detector and drop wire guide, either one or both, is preferably formed as a yielding spring which will tend to assume its original position after having been deflected by a drop wire.

More specifically stated, the engaging member of the detector and the drop wire guide is preferably formed of a coiled wire spring which is expansible and contractable, so that when a drop wire fails to be supported by a warp thread and it has dropped into engagement with the drop wire guide, it will rest on or between the convolutions of the coil, so that by longitudinal expansion of the drop wire guide the position of the defective warp thread is at once ascertained.

The above and other new features of the invention and novel combination of parts will best be made clear from the following description and the accompanying drawings of one good form thereof.

In the drawings:

Fig. 1 is a fore-and-aft section through a loom containing the present invention;

Fig. 2 is an enlarged perspective detail showing a warp stop mechanism containing the present invention;

Fig. 3 is an enlarged cross-section of the main portion of the warp stop mechanism, showing more particularly one form of the detector lock;

Fig. 4 is a perspective detail showing the invention as associated with the hair-pin type of drop wire and the condition that ensues when a drop wire fails to be supported by a warp thread;

Fig. 5 is a perspective view showing one form of the detector and its associated parts;

Fig. 6 is a sectional detail showing one

convenient form of means for detachably connecting either the drop wire guide and end supports or the ends of the flexible or yielding drop wire engaging member of the detector; and

Fig. 7 is a cross-sectional view on an enlarged scale showing a modified form of the detector lock.

The warp stop mechanism of the present invention may be associated with any type of transmission mechanism for stopping the loom when the detector is stopped in its movement by being locked to a fixed part, but in the present instance the loom frame 1 has mounted thereon the usual shipper 2 against which bears the end 3 of a crank lever 4 pivoted at 5 near the shipper 2. The crank of the lever 4 is connected at 6 with a transmitter 7, movement of which to the left, Fig. 1, will cause the shipper to be detached from its holding notch and the loom be stopped.

The lay 8 has adjustably mounted thereof the bunter 9 which is adapted at times to engage with the end of the dog, as will be explained.

Rising from the loom frame 1 is a supporting bracket 10 in which the shaft 11 is mounted for rocking movement. The outer end of the shaft 11 is secured to a slotted lifter 12, Fig. 2, into the slot of which projects a pin 13 extending from the dog 14 which is carried by the shaft 11. As shown, the dog 14 has a slot 15 through which the shaft 11 projects, the construction being such that should the dog be struck by the bunter 9 it may be moved thereby to effect loom stoppage. Also mounted on the shaft 11 is the arm 16 through the slot of which, similar to the slot 15 of the dog, extends the shaft 11. The arm 16 has an arcuate slot 17 into which extends a pin 18 from the dog 14, the construction being such that should the dog 14 be lifted into the path of the bunter 9, as the lay moves back, both the dog and the arm 16 will be moved rearwardly, as shown, and thereby draw rearwardly on the transmitter 7 which is connected at 19 to the arm 16.

Secured to the rock shaft 11 is an arm 20 to which is pivotally connected the rod 21 which is under control of the main portions of the warp stop mechanism as will appear.

Mounted at each side of the loom on a bracket 22 are the end frames 23 of the main warp stop mechanism, only one of which, however, is shown. The end frame 23 may be secured to the bracket 22 adjustably by the bolt and slot connection 24.

Mounted in extensions 25 of the end frames 23 is a rock shaft 26 on which is loosely mounted the cam 27, Fig. 2, which engages a projection 28 secured to the rock shaft 26. The projection 28 and cam 27

have interengaging cam surfaces, and the loose cam 27 is normally pressed into engagement with the projection or cam 28 by a spring 29 interposed between a collar 30 secured to the rock shaft 26 and the cam 27. The cam 27 has a lug or arm 31 to the outer end of which is connected the operating rod 32 which may be actuated from any going part of the loom, not herein shown, because it is well understood by those familiar with warp stop mechanisms that the actuating rod is given its endwise movement by suitable means, such as a cam.

Mounted on the stud 33 extending upwardly from the extension 25 is a rocking sleeve 34 carrying an arm 35 which is connected to the transmitter 21 at 36. The sleeve 34 has another arm 37, Fig. 2, angularly disposed relative to the arm 35 and connected to a rod 38, the other end of which is secured to the cam 27, the construction being such that should the rock shaft 26 be arrested in its rocking movement while the cam 27 continues to be actuated, the cam 27 will be moved endwise on the rock shaft 26 and through the rod 38 and connections described, position the dog 14 to be struck by the bunter 9 as the lay moves back.

The rocking movement of the rock shaft 26 is utilized in the present invention for imparting detecting movements to the detector, and as shown, Fig. 2, the shaft 26 has an arm 39 extended therefrom which is connected by a rod 40 to the detector frame, the construction being such that rocking movement of the rock shaft 26 will impart a to-and-fro movement to the detector.

Extending downwardly from the bracket or projection 25 is a lug 41 to which is rigidly secured a support 42 on which the detector moves.

The detector or detector frame is of novel construction, as shown more particularly in Figs. 3 and 5. In the present instance of the invention, the detector frame comprises the cross-bars 43, 44 which are shown as formed of angle iron, but of course they may be variously contrived. Secured to and extending upwardly from the cross-bars 43 and 44 is a saddle 45 through the opening 46 of which extends the support 42. The number of saddles, and consequently, the number of supports for the detector frame may vary, but in the present instance of the invention, as indicated in Fig. 5, four of such saddles are shown, and more or less may be used in accordance with the width of the loom and the consequent size of the detector frame.

The detector bars 43 and 44 have interposed therebetween suitable spacers which permit either of the detector bars to tilt or move angularly relative to the other. In the present instance of the invention, where the detector bars are formed of sheet metal or angle iron, as shown, each bar has

a flattened portion 47 at intervals, and between such flattened portions of the detector bars is interposed a spacer 48 which may be formed conveniently of a tube, as indicated in Fig. 3, and when formed of tubing, as shown, such spacers may provide a housing for spring means which holds the detector bars 43, 44 in their spaced relation with permissive relative tipping movement. In the present instance a spring 49 extends through each of the spacers 48, and its end portions are connected to the detector bars. As shown, the ends of the spring 49 are carried through openings in the detector bars and have their end portions 50 turned into engagement with the detector bars, as indicated in Fig. 3. The construction is such that while the spacers maintain the detector bars in spaced relation and bear with their end portions upon the flattened sides of the detector bars, as described, the latter may tilt yieldingly under the action of the springs 49. Obviously, the number of spacers and springs employed may vary with the extent and size of the detector frame.

Each detector frame carries a locking device for locking the detector frame to a fixed part when either of said frames is tilted relative to the other on its support. As shown in Fig. 3, the saddles 45 carried by each detector bar are provided with rollers or pins 51 which rest upon the support 42 and the space between the rollers or pins 51 and the top portion 52 of the detector bars is such that should either detector bar be tilted, the pins or rollers 51 and top portion 52 of the detector bar will lock the detector bars to the support and thereby arrest further detecting movement.

Each detecting bar of the detector frame carries a drop wire engaging member which will contact with a drop wire when it fails to be supported by a warp thread, and cause the connected detector bar to be tilted upon its support and consequently locked to prevent further detecting movement.

Inasmuch as the drop wires are usually formed of light metal or other light material, injury is liable to occur to a drop wire should the entire strain of arresting the detector be borne thereby, and the present invention contemplates a drop wire engaging member formed of flexible material sufficiently resilient to prevent injury to the engaging drop wire and yet sufficiently inflexible to cause the drop wire to actuate the detector lock. In the present instance of the invention, the drop wire engaging member is formed of coiled wire sufficiently flexible to avoid injury to an engaged drop wire and similar in construction to flexible tubing. Should the drop wire engaging spring itself be bent or deflected by a drop wire, it will at once re-

sume its original straight condition, owing to the spring character of the coiled wire, when the pressure is removed.

As indicated more particularly in Figs. 5 and 6, the drop wire engaging member 53 is formed of closely coiled flexible wire which is detachably connected to the associated detector bar. In the present instance, each coiled wire which constitutes the engaging member of the detector has secured at its ends a hook 54 having its end portion bent as at 55 and 56 to engage in an open recess 57 and a hole 58 formed in one of the lugs or projections 59 extending from the detector bars, the construction being such that the engaging member 53 of the detector may be readily detached from or attached to its associate detector bar.

It may be desirable in some cases to additionally support the flexible coiled wire between its ends, and for this purpose the detector frames 43, 44 may be provided with upstanding lugs 60 having recesses or seats 61 for engaging the wire coil between the ends thereof. Any number of such additional supports may be employed, in accordance with the length or size of the detector frame, as indicated in Fig. 5.

From the construction thus far described, it will be apparent that should a drop wire fail to be supported by a warp thread it will be met by the drop wire engaging member of the detector with a light and yielding pressure, sufficient, however, to operate the detector lock, whereupon the detector is arrested by the lock to effect loom stoppage, as hereinbefore explained.

As indicated in Fig. 3, the side supporting frame of the main warp stop mechanism is provided with warp supports 62 over which the warp threads *a* pass from the warp beam to the harnesses. As indicated in Fig. 3, each of the drop wires 63 may be formed with an eye 64 through which the warp thread passes and by which the drop wire is held or supported by a warp thread.

In mechanical warp stop mechanisms it is usual to provide a drop wire guide for each row of drop wires, in order to direct them in their movement when unsupported by a warp thread, and the present invention provides a novel construction of drop wire guide.

Each drop wire guide is formed of a flexible coiled wire 65, the end portion 66 of which is bent in a manner similar to that already described for the drop wire engaging member of the detector, and as shown in Fig. 6. This construction forms a convenient means for disengaging the end of the drop wire guide from the end support and drawing it lengthwise, to thereby indicate the position of the unsupported drop wire and the imperfect warp thread.

When a drop wire fails to be supported by a warp thread, it will take the position of the lower drop wire, indicated in Fig. 3, and will contact with the flexible wire constituting the engaging member of the detector and thereby operate the lock to lock the detector to a fixed part of the loom. At such time the upper end portion of the drop wire through the slot 67 of which the drop wire guide extends, will engage the convolutions of the drop wire guide, and at such time should the drop wire guide be detached from its end support and pulled lengthwise, it will separate the fallen drop wire from its associates and indicate the warp fault. So, also, when the end of the flexible drop wire guide is engaged with its support, the contracting force of the coiled wire will cause the drop wire guide to contract, and hold the drop wire guide in position by the contractile force of the spring. So, also, should the drop wire guide be deflected or bent, its flexible and yielding nature will permit it to automatically straighten under the contractile force of the spring.

In some cases it may be desired to use the hair-pin type of drop wire, as indicated in Fig. 4, wherein the drop wire 68 has an opening 69 for the coiled spring drop wire guide 70, and its lower end portion 71 is formed of two legs unconnected at their lower ends. Such form of drop wire may be supported by the warp thread *a* by passing the latter through the upper portion of the slot separating the lower leg portion of the drop wire, as indicated in Fig. 4.

When the hair-pin form of drop wire is employed and fails to be supported by a warp thread, its lower leg portion will be engaged by the coiled wire constituting the drop wire engaging member of the detector, as indicated in Fig. 4; but the yielding nature of such detector is such that it will not injuriously distort the hair-pin drop wire but will deflect it somewhat, as indicated in Fig. 4, to indicate the position of the warp thread.

Fig. 7, as hereinbefore stated, shows a modified form of the detector lock in which, instead of the pin or roller 51 and the upper edge portion 52 of the detector bars engaging the fixed support on which the detector has its detecting movement, each detector bar, otherwise similar to that already described, has the lock formed by upwardly extending wing portions 72 which are secured to each of the detector bars. Adjacent to the upwardly extending end portions 72 of the modified form of lock is a serrated bar 73 which may be conveniently secured above the detector and warp supports 62, the construction being such that should a drop wire fail to be supported by its warp thread, it will, as in the preferred

form of the invention, cause one of the detector bars 43, 44 to be tilted to thereby actuate the lock and cause the end portion 72 thereof to engage and be held by the fixed toothed bar 73.

A troublesome factor in the warp stop mechanisms for looms is the accumulation of lint on the moving parts, especially on the drop wire engaging member, the drop wire guides or drop wire, but in conformity with the present invention the drop wire guides and drop wire engaging member of the detector afford ready means for shedding any lint that may accumulate thereon and for discharging such lint by the expansive and contractile movement of the springs which form such parts.

What is claimed is:

1. In a mechanical warp stop mechanism for looms, the combination of a series of drop wires normally supported by the warp threads during weaving, a drop wire detector having a detecting movement, means actuated by the drop wire when it fails to be supported by a warp thread for securing the detector to a fixed part to thereby arrest its detecting movement, and means for stopping the loom when the detector is secured to the fixed part and its movement is thereby arrested.

2. In a mechanical warp stop mechanism for looms, the combination of a series of drop wires normally supported by the warp threads during weaving, a drop wire detector having a detecting movement, a detector lock which is actuated by a drop wire when it fails to be supported by a warp thread for connecting the detector immovably to a fixed part to thereby arrest detecting movement of the detector, and means for stopping the loom when the detector is locked to the fixed part and its movement is thereby arrested.

3. In a mechanical warp stop mechanism for looms, the combination of a series of drop wires normally supported by the warp threads during weaving, a drop wire detector having a detecting movement, a detector lock movable with the detector and actuated by a drop wire when it fails to be supported by a warp thread for locking the detector to a fixed part to thereby arrest the detecting movement of the detector, and means for stopping the loom when the detector is locked to the fixed part and its movement is thereby arrested.

4. In a mechanical warp stop mechanism for looms, the combination of a series of drop wires normally supported by the warp threads during weaving, a drop wire detector having a detecting movement, a detector lock carried by the detector and actuated by a drop wire when it fails to be supported by a warp thread, a fixed part with which the lock engages when actuated

5 by a drop wire to thereby arrest detecting movement of the detector and relieve the strain on the drop wire, and means for stopping the loom when the detector movement is arrested.

10 5. A warp stop motion detector having a detecting movement and a detector lock for connecting the detector to a relatively fixed part to thereby arrest its detecting movement and relieve the drop wire when it fails to be supported by a warp thread.

15 6. A warp stop motion detector having a detecting movement, a lock for securing the detector to a fixed part, and a drop wire for actuating the lock to thereby arrest movement of the detector and relieve strain upon the drop wire.

20 7. In a warp stop mechanism for looms, the combination of a series of drop wires, a drop wire detector having a detecting movement and comprising a yielding member adapted to engage a drop wire when it fails to be supported by a warp thread, and a lock actuated through said yielding member to lock the detector to a fixed part to thereby arrest its movement, and means for stopping the loom when the detector is locked to the fixed part.

25 8. A warp stop motion detector comprising a frame, a lock mounted on the frame for movement into and out of locking position, means normally acting to hold the lock out of locking position, a fixed member adapted to be engaged by said lock when moved into locking position, and a series of drop wires normally supported by the warp threads during weaving and adapted to move the lock to locking position into engagement with the fixed member when a drop wire fails to be supported by a warp thread during movement of the detector that the fixed member may take the stopping strain off the drop wire.

30 9. A detector for mechanical warp stop mechanisms, comprising a frame having detecting movement, a support for said frame relative to which it has a tilting movement when a drop wire fails to be supported by the warp thread, and a lock carried by the frame for engagement with a fixed part to arrest the detecting movement of the detector when the frame is tilted on its support to thereby relieve the strain on the drop wire.

35 10. In a warp stop mechanism for looms, the combination of a series of drop wires normally supported by the warp threads during weaving, a detector having a detecting movement and provided with a yielding drop wire engaging member formed as a coiled spring, and means for stopping the loom when a drop wire fails to be supported by a warp thread during weaving.

40 11. In a warp stop mechanism for looms, the combination of a series of drop wires

normally supported by the warp threads during weaving, a detector having a detecting movement and provided with a yielding drop wire engaging member formed as a coiled spring, means for stopping the loom 70 when a drop wire fails to be supported by a warp thread during weaving, and a lock which is actuated to lock the detector and arrest its movement when the coiled spring engages a drop wire. 75

12. A detector for mechanical warp stop mechanism, comprising a detector frame, means for imparting a detecting movement to said frame, a relatively yielding drop wire engaging member carried by the detector frame for yieldingly engaging a drop wire when it fails to be supported by a warp thread, and means actuated by the yielding drop wire engaging member for arresting movement of the detector frame. 80

13. A detector for mechanical warp stop mechanism for looms, comprising a frame, and an expansion and contraction spring carried by the frame and constituting the drop wire engaging member of the detector. 85

14. A detector for mechanical warp stop mechanism for looms, comprising a frame, an expansion and contraction spring carried by the frame and constituting the drop wire engaging member of the detector, and means for securing the expansion spring to the frame by the contractile force of the spring. 90

15. In a warp stop mechanism for looms, the combination of a series of drop wires normally supported by the warp threads 100 during weaving, a drop wire guide for guiding the drop wires, a detector having an expansion spring constituting the drop wire engaging member of the detector, and means for stopping the loom when the detector is arrested in its detecting movement. 105

16. In a warp stop mechanism for looms, the combination of a series of drop wires normally supported by the warp threads during weaving, a drop wire guide for guiding the drop wires formed as an expansion spring, a detector having an expansion spring constituting the drop wire engaging member of the detector, and means for stopping the loom when the detector is arrested in its detecting movement. 110

17. In a warp stop mechanism for looms, a drop wire guide formed as a coiled spring for engaging a drop wire when it fails to be supported by a warp thread and for locating such unsupported drop wire by deflection of the spring. 120

18. In a warp stop mechanism for looms, the combination of a supporting frame, a drop wire guide formed as an expansion and contraction spring for engaging a drop wire when it fails to be supported by a warp thread and acting when deflected to locate the unsupported drop wire. 125

19. In a warp stop mechanism for looms, 130

- the combination of a series of drop wires normally supported by the warp threads during weaving, a drop wire guide, a detector having a detecting movement and provided with a drop wire engaging member constituted as a coiled spring which yields laterally when a drop wire fails to be supported by a warp thread and is engaged by the drop wire engaging member.
20. In a warp stop mechanism for looms, the combination of a series of drop wires normally supported by the warp threads during weaving, a drop wire detector, a fixed support on which the detector has a detecting movement, a lock which is actuated by a drop wire when it fails to be supported by a warp thread to lock the detector to its fixed support and thereby arrest its detecting movement to relieve the drop wire from strain, and means for stopping the loom when the detector is locked to its support.
21. In a warp stop mechanism for looms, the combination of a series of drop wires normally supported by the warp threads during weaving, a drop wire detector, a rocker connected to the detector for imparting detecting movements thereto, a projection fixed to the rocker, a cam loosely mounted on the rocker and engaging said projection, means for operating the cam and
- through it the rocker, a lever having positive connection with the cam and actuated by the cam to effect loom stoppage when the drop wire detector is arrested in its movement by a drop wire.
22. In a warp stop mechanism for looms, the combination of a series of drop wires, a detector having a detecting movement and provided with a relatively elastic drop wire engaging member, and means for stopping the loom when a drop wire fails to be supported by a warp thread during weaving.
23. In a mechanical warp stop mechanism for looms, a detector having a detecting movement and provided with a spring constituting the drop wire engaging member of the detector.
24. In a warp stop mechanism for looms, the combination of a series of drop wires, a drop wire detector, means for imparting reciprocating detecting movement to the detector, a locking member movable with the detector and actuated to connect the detector immovably to a fixed part to arrest detecting movement of the detector and relieve the strain on the drop wire when it fails to be supported by a warp thread.

In testimony whereof, I have signed my name to this specification.

CARL D. BROWN.
